UNITED STATES PATENT OFFICE.

JAMES CARRIE, OF BUTLER, PENNSYLVANIA, ASSIGNOR TO WILLIAM D. SAWYER, OF
MILWAUKEE, WISCONSIN.

GRINDING AND POLISHING MACHINE.

Application filed April 5, 1921. Serial No. 458,859.

To all whom it may concern:

Be it known that I, JAMES CARRIE, a subject of Great Britain, and resident of Butler, in the county of Butler and State of Pennsylvania, have invented certain new and useful Improvements in Grinding and Polishing Machines; and I do hereby declare that the following is a full, clear, and exact description thereof.

10 My invention refers to new and useful improvements in machines for grinding and polishing slabs or plates of material, such as for example as marble, glass or the like, and the invention particularly pertains to machines of the above character as disclosed in my patent for improvements in grinding and polishing machines, No. 1,375,129, patented April 19, 1921.

15 The particular object of my present invention is to provide a plurality of burnishing shoes having a compound planetary action upon the work, whereby the time required for completing a grinding and polishing operation is materially reduced, thus increasing the efficiency of the machine to a maximum without materially increasing the cost thereof.

20 With the above and other minor objects in view, the invention consists in certain peculiarities of construction, combination of parts as are hereinafter set forth with reference to the accompanying illustrations and subsequently claimed.

25 In the drawings:

20 Figure 1 represents a fragmentary sectional elevation of a grinding and polishing machine embodying the features of my invention, the section being indicated by line 1-1 of Figure 2.

40 Figure 2 is a sectional plan view of the same, the section being indicated by line 2-2 of Figure 1, and

Figure 3 is a diagrammatic bottom plan view of another form of my invention.

45 Referring by characters to the drawings, 1 represents an overhead frame, which frame is associated with a reciprocated table 2 for supporting the slabs to be burnished and polished.

50 The table structure in this case forms no part of my invention. The frame 1 is provided with a top bearing 2, an intermediate bearing 2' and a lower bearing 2'' for a master drive shaft 3. Mounted in the journal 55 2' is the hub of a drive gear wheel 4, which

hub is in spline connection with the main drive shaft. Hence, it will be seen that the gear wheel 4 will impart rotary motion to the shaft 3, while at the same time said shaft is capable of longitudinal movement 60 within the gear hub. The upper end of the shaft is extended through a threaded sleeve 5, which sleeve is loosely mounted within the bearing 2 and is engaged by the threaded hub of an adjusting gear wheel 5'. The upper end of the shaft is supported by nuts or collars 6, which are in threaded union with said end, whereby a predetermined longitudinal adjustment of the shaft is had, and the said main drive shaft is intermittently adjusted vertically by rotation of the gear wheel 5' about the threaded sleeve 5, whereby a series of burnishing shoes to be hereinafter referred to, are micrometrically adjusted with relation to the face of the 75 plate to be burnished or polished.

70 The lower end of the main drive shaft 3 has secured thereto a master head 7, which master head, as shown in Figures 1 and 2, at its outer end, is formed with hubs 7' that 80 constitute journals for vertically disposed arbors 8. The upper ends of the arbors have secured thereto gear wheels 9, which gear wheels are meshed with intermediate gear wheels 10 that are journaled upon 85 studs extending from the master head. The gear wheels 10 are meshed with a master gear wheel 11, which gear wheel is keyed or otherwise secured to a sleeve portion of the frame bearing 2''.

90 In this exemplification of my invention, it is understood that the master head is formed with four arms having a pair of arbors journaled in each.

95 The lower ends of the arbors 8 have each secured thereto burnishing heads 12, each of which heads as shown in Figures 1 and 2 are formed with a pair of arms only. The ends of the burnishing head arms terminate with bearing sleeves 13, which bearing 100 sleeves form journals for vertically disposed spindles 14. The lower end of each spindle has secured thereto a burnishing shoe 15 and the upper ends thereof carry gear wheels 16, which gear wheels are meshed with idle gear wheels 17, the same being loosely journaled upon studs that project from the arms of the burnishing heads. The idle gear wheels 17 are in turn meshed with auxiliary gear wheels 18, which gear wheels are axi- 110

ally positioned with relation to the arbors 8, and are secured to the lower ends of the master head hubs 7.

From the foregoing description, it will be observed that when the main drive shaft 3 is rotated, the arbors 8 have imparted thereto a planetary motion with relation to the axis of the master head, due to their gear train connection back to the fixed master gear wheel 11. The arbors 8 in turn cause rotation of the burnishing heads, whereby a planetary motion is imparted thereto. When this planetary motion develops about the main drive shaft, it would be observed that the gear train connection between the auxiliary fixed gear wheel 18 and the burnishing shoes, will cause said burnishing shoes to revolve about their own axis, and at the same time they will be rotated about the axis of their burnishing heads. Thus a double planetary movement is developed whereby the burnishing shoes are rapidly revolved so as to cover the surface burnished thoroughly and to thus increase the speed of the machine, as a whole.

It follows that the burnishing heads carrying the shoes may be revolved in either direction, depending upon an arbitrary selection of driving gears, and that this same result can be varied by different arrangements of the train of gears, with respect to the main drive shaft.

Referring particularly to Figure 3, it will be observed that the burnishing heads are formed with four arms, and in this exemplification of my invention, the fixed master gear wheel and fixed auxiliary gear wheel impart direct drive to the burnishing shoes, whereby their direction of rotation is varied from the direction of rotation shown by the structure in Figures 1 and 2. In other words, in this last exemplification of my invention, the idle or intermediate gear wheels are dispensed with. Obviously, the train of gears for carrying out my invention may be varied to produce greater or less speed,

and also to vary the direction of travel of the burnishing shoes with relation to their movement about the main drive shaft.

While I have shown and described certain exemplifications of my invention, as to detail, obviously I may, without departing from the spirit of it, vary the structural features within the scope of the claims.

I claim:

1. A grinding and polishing machine comprising a vertically adjustable main drive shaft, a master head revolvable with the main drive shaft, a fixed master gear positioned above said master head, a plurality of vertically disposed arbors journaled in the master head in gear connection with the master gear wheel, a burnishing head secured to each arbor, an auxiliary gear wheel positioned axially about each arbor, a series of vertically disposed spindles journaled in each burnishing head, each being in gear connection with its associated auxiliary gear, and a burnishing shoe secured to the lower end of each spindle.

2. A grinding and polishing machine comprising a vertically adjustable main drive shaft, a master head revolvable with the main drive shaft, a fixed master gear positioned above said master head, a plurality of vertically disposed arbors journaled in the master head in gear connection with the master gear wheel, a burnishing head secured to each arbor, a fixed auxiliary gear wheel positioned axially about each arbor and secured to its associated burnishing head, a series of vertically disposed spindles journaled in each burnishing head, each being in gear connection with its associated auxiliary gear, and a burnishing shoe secured to the lower end of each spindle.

In testimony that I claim the foregoing I have hereunto set my hand at Butler, in the county of Butler and State of Pennsylvania.

JAMES CARRIE.
